UNITED STATES PATENT OFFICE.

CLIFFORD H. OAKLEY, OF TRENTON, NEW JERSEY.

MATTING.

997,319.

Specification of Letters Patent. Patented July 11, 1911.

Application filed August 8, 1910. Serial No. 576,202.

To all whom it may concern:

Be it known that I, CLIFFORD H. OAKLEY, a citizen of the United States, and a resident of the city of Trenton, in the State of New Jersey, have invented certain new and useful Improvements in Matting, of which the following is a specification, reference being had to the accompanying drawings, forming a part hereof.

10 The object of the invention is to provide a sectional matting, that is one composed of separate pieces, which shall be easy to assemble so that a mat of any size or shape may be quickly put together; which shall lend itself readily to the incorporation of 15 various designs and lettering; which shall be easy to repair and to dis-assemble for the purpose of substituting new sections for worn out ones; and which shall be conveniently flexible and foldable for the purpose 20 of storing and transportation.

In the drawings, which show several embodiments of the improvements, Figures 1-4 are plan views illustrating different forms, 25 Fig. 1 being broken away to show the fastening and strengthening ribs more clearly. Figs. 5 and 6 are end views respectively corresponding to Figs. 3 and 4. Fig. 7 is a plan view of still another modification. 30 Fig. 8 is a similar view illustrating the use of units each embodying two colors, in the formation of letters or designs. Figs. 9 and 10 are detail views of one of the fastening rods and collars. Figs. 11 and 12 are 35 respectively plan and side views, partly broken away, of one of the units employed to constitute the matting. Fig. 13 is a plan view showing such a unit with a corrugated surface, and, Figs 14 and 15 are respectively 40 a top plan and a sectional view of a unit having a metallic tread piece embedded therein.

From Fig. 1, which embodies what is considered to be the preferable form of the 45 improved matting, it will be seen that each unit *a* thereof is provided with a strengthening rib *b*, of steel wire or some other suitable material, which is embedded therein and the ends of which project from the opposite 50 ends of the unit as two eyes *c*. It will also be seen that the units are arranged in columns and rows, or what is the same thing,

aligned lengthwise and crosswise, and that between each column a rod *d* is passed through the eyes presented thereto by the 55 ends of the units which oppose or face each other.

It is not necessary, of course, in carrying out the invention, to arrange the units *a* in columns and rows; and, in fact, for purposes of designing or embodying in the matting some form of ornamentation or lettering, a staggered arrangement may be preferable to one in which the alinement is preserved up and down or across, or both up 60 and down and across; but from the standpoint of assembling, it is simpler to have the column arrangement as shown in Fig. 1 than the staggered arrangement, for instance, of Fig. 7. The assembling in the 65 case of the form shown in Fig. 1 may be done by simply laying the units in long grooves provided in assembling frames (not shown), and then running the rods *d* through the eyes *c* which latter are brought 70 into alinement by the relative location of the grooves; and finally, securing fastening collars *e* to the ends of the rods. The whole operation of assembling only requires a few moments even for a large size mat. If an 75 end or finishing strip of tapering form is to be applied, this may be done conveniently by making such strip in the form shown in Figs. 4 and 6 where it will be seen to be provided with recesses *f* upon its inner side, 80 which register with the eyes *c* presented thereto by the side of the mat. Of course, 85 it will be possible to apply separate tapering pieces instead of the integral strip, such a form being illustrated in Figs. 3 and 5. 90 Instead of finishing the sides of the mat by providing a tapering strip or strips the rods at the sides may be covered with tubular pieces *g* of rubber or other material, 95 one such piece being arranged between each two adjacent eyes. (See Figs. 1 and 2).

For convenience in assembling and handling it is preferable to have the units *a* integrally united in groups of two, three, four or more, four being shown as so united in 100 Fig. 1. Fig. 2 shows the units separated, and, in this condition they obviously lend themselves to greater complexity of design and to more ready assemblage into some

form of lettering. Where design or lettering is unimportant, however, it will generally be found desirable to form the units in groups of four or more, the finished mat 5 presenting substantially the same appearance in either case.

To secure transverse alinement of the units, or alinement in rows, the eyes *c* are slightly offset from the transverse center 10 line through each unit. This may be done, as shown in Figs. 1 and 2, by locating the rib *b* to one side of the transverse center line or by running it through the unit diagonally, as shown in Figs. 11-15. Where 15 the ribs are located along a line slightly offset from the center line, as in Fig. 1, the units in one column are arranged with the ribs slightly in advance of the center line and in the two adjacent columns with the 20 ribs slightly behind the center line, thus bringing the corresponding eyes into an overlapping position so that their openings register, as shown. Where the arrangement shown in Figs. 11-15 is adopted, the eye on 25 one side of a unit is slightly in advance of the center and the eye on the other side slightly behind the center, so that the units in each column are interchangeable without reversing.

30 It will be understood that a matting made in accordance with the improvements is freely flexible and may be rolled up when not in use. If flexibility in more than one direction is desired, the rods *d* may be divided at suitable intervals and links *h* inserted (see Fig. 3). In order to secure the collars *e* upon the rods, the former are bored radially as at *i* to a diameter greater than that of the rods, and, when a collar has 35 been placed upon a rod, a suitable tool is inserted through the radial bore *i* and by means of a blow the metal of the rod is spread or expanded into the bore *i*, as at *m*. (See Figs. 9 and 10).

45 The material of which the units are composed may be selected with regard to the use which is to be made of the matting. For general use, rubber will ordinarily be found preferable. Fig. 13 illustrates a rubber unit with a corrugated face or tread *n* and a monogram *o*. In Figs. 14 and 15, a metallic piece, such as a lead disk *p*, is shown inserted or embedded in the rubber with its face flush with the tread surface of 50 the rubber, so as to form a non-slipping tread. In such a case, for the purpose of assembling the parts, the lead disk is formed with a slot *r* which fits over the rib *b*, the slot facing the underside of the unit, so 55 that the tread surface of the disk is unbroken. In Fig. 8, the units *a'* are indicated as being of two different colors, as may be desirable for the formation of some letters or for some designs.

60 65 In any embodiment of the invention, it

should be observed that the rods *d* and ribs *b* will form a frame or skeleton for the tread pieces or units *a*, the latter simply clothing the ribs and not being subjected to any strains whatever as all the strains are borne 70 entirely by the frame. It should be observed, too, that each rib, running as it does from end to end in the corresponding tread piece, constitutes a sort of back-bone for such piece. The latter, in other words, is 75 built up around or formed upon this rib and is thus not only strengthened and supported thereby but its shape is effectively preserved. It will be obvious that where the tread pieces are made out of soft rubber, as 80 is generally the case, some sort of shape-preserving means must be provided, and a single rib, such as a piece of wire extending from end to end, furnishes a particularly simple and convenient means of this sort. 85 In the present case, where these ribs are provided with eyes at either end to constitute part of the fastening means whereby the several units are attached together, the construction of the matting is rendered particularly simple and convenient. 90

It will be understood that various other modifications of the invention are possible, the precise arrangement, design and character of matting depending to a large extent 95 upon the particular circumstances of use.

I claim as my invention:

1. In a matting having a plurality of pieces constituting the matting proper and eyes projecting from opposite ends of each piece, the combination of rods to unite the eyes in the ends facing each other, and fastening collars upon the rods bored radially, the said rods being expanded into the bores 100 to retain the collars. 105

2. In a matting, the combination of a plurality of rubber pieces constituting the matting proper, a metallic piece embedded in each rubber piece and having a slot, and a transverse rib also embedded in each rubber piece and extending through the slot 110 in the corresponding metallic piece. 115

3. A mat comprising a frame of rods and ribs, and a plurality of tread pieces, the latter being arranged longitudinally around 115 the ribs each of which thereby forms a backbone for the corresponding tread piece, and the rods running transversely of the ribs to unite the same together.

4. The combination of a skeleton for a matting comprising a plurality of parallel ribs having looped ends, and rods arranged transversely of the ribs and passing through the loops to unite the ribs together, and a plurality of tread pieces in which the ribs are embedded longitudinally to constitute means for preserving the shape of as well as strengthening and supporting means for the tread pieces. 120 125

5. The combination of a metallic skeleton 130

for a matting comprising a plurality of parallel wires having looped ends, and rods arranged transversely of the wires and passing through the loops to unite the wires together, and a plurality of soft rubber pieces in which the ribs are embedded longitudinally to constitute means for preserving the shape of the rubber pieces as well

as strengthening and supporting means for said pieces.

This specification signed and witnessed this 5th day of August A. D. 1910.

CLIFFORD H. OAKLEY.
